MEANS FOR SEALING THE EDGE OF A
PANEL TO FRAME MEANS
Alfonse Butler, 4306 Maycrest Ave.,
Los Angeles 32, Calif.
Filed July 9, 1962, Ser. No. 203,456
5 Claims. (Cl. 160—40)

Generally speaking, the present invention relates to an edge-sealing apparatus or means for sealing the edge of a panel to an effective frame means or portion surrounding an aperture in a wall.

More particularly, in one preferred form of the invention, the aperture in the wall may comprise a window aperture and the effective frame means surrounding same may comprise a window frame means or casing means adapted to receive, in an edge-sealed manner, the panel which, in one specific exemplary form of the invention, may comprise a window screen panel. However, said panel may comprise a storm window panel, or any other panel, and the word "panel," as used herein, is to be so construed.

The window frame or window casing means (and the associated window means) may be of any suitable type such as a storm window type, a conventional single panel window type, or any other type and also may be of a form not normally adapted to be opened or may be of a type adapted to be opened whenever desired in any of several different manners. For example, it may be of the sliding sash window type, or of any of the various pivotally mounted single or multiple panel window types, or of any of the louvered or jalousie window types, or of any other type.

Furthermore, it should be noted that, while one exemplary preferred form of the invention referred to in considerable detail hereinafter comprises a form wherein the aperture is a window aperture, the frame means is a window frame means or window casing, and the panel is a window screen panel, this is for exemplary purposes only and it should be clearly understood that the invention is not specifically so limited.

It should be clearly noted that an edge-sealed window screen is highly advantageous because of the fact that it positively excludes all types of small insects and other pests which frequently manage to pass the relatively loose unsealed edges of conventional prior art window screens.

It should also be noted that such edge-sealing is also extremely important for a storm window for much the same reasons, plus the weather isolation feature and/or thermal barrier feature required therein.

Furthermore, this type of edge sealing provides a relatively solid, non-vibratory, and non-rattling connection between the window screen (or storm window) panel and the window frame so that it will not rattle or vibrate as a result of the presence of high intensity winds or other sources of vibration.

It is an object of the present invention to provide novel edge-sealing means of the character referred to above which is adapted for quick and easy attachment with respect to a window frame or window casing portion of a wall surrounding and defining a window aperture therein whereby to provide an arrangement for normally completely sealing the edges of a window screen panel or storm window panel.

It is a further object of the present invention to provide novel edge-sealing apparatus of the character referred to hereinbefore, which includes framework means adapted to be quickly and easily attached with respect to window frame or window casing means (or portions) of a wall surrounding and defining a window aperture therein and which is additionally provided with compressible, elastomeric sealing gasket strip means positioned

2

with respect to said framework means for forcible abutment with corresponding edges of a window screen panel or storm window panel supported by the framework means whereby to provide positive edge-sealing engagement of said gasket strip means and said window screen or storm window panel means around the complete periphery thereof when fully assembled with the window screen or storm window panel in fully closed, locked and retained relationship relative to the framework means and the sealing gasket strip means.

It is a further object to provide novel edge-sealing apparatus of the character referred to above, which is so constructed as to be adaptable to being sold in what might be termed a "kit" or a "do-it-yourself" disassembled form consisting of various lengths of the individual elements of the apparatus which, when assembled, define the complete apparatus and which can be purchased in rough or finished pre-cut form or which can be cut at the time of purchase or installation to various different sizes or lengths suitable for assembly so as to comprise the complete apparatus in a size exactly right for a particular window frame or window casing surrounding and defining a particular window aperture in a wall. However, the invention is not specifically so limited, and it may be sold in prefabricated, substantially completely assembled form if desired.

It is an object of the present invention to provide novel panel-edge-sealing apparatus or means for sealing the edge of a panel with respect to the corresponding edge of an aperture in a wall, and which embodies the broad generic features referred to above and/or any of the specific aspects thereof referred to above and which is of relatively simple, inexpensive, easy-to-manufacture, and easy-to-install construction such as to be conducive to widespread use thereof.

Further objects are implicit in the detailed description which follows hereinafter (which is to be considered as exemplary of the invention but not specifically limiting it) and said objects will be apparent to persons skilled in the art after a careful study of the detailed description which follows hereinafter.

For the purpose of clarifying the nature of the present invention, two exemplary embodiments are illustrated in the hereinbelow-described figures of the accompanying single drawing sheet and are described in detail hereinafter.

FIG. 1 is a greatly reduced-size view of one exemplary embodiment of the present invention in fully assembled and mounted relationship with respect to a window frame means or portion surrounding a window aperture in a wall, which is shown fragmentarily.

FIG. 2 is a larger-scale, fragmentary, cross-sectional view, taken in the direction of the arrows 2—2 of FIG. 1.

FIG. 3 is an enlarged, fragmentary sectional view of the upper left corner of the apparatus of FIG. 1, taken in the direction of the arrows 3—3 of FIG. 1.

FIG. 4 is an enlarged fragmentary sectional view of a central bottom portion of the apparatus of FIG. 1 adjacent the bottom edge thereof and is taken in the direction of the arrows 4—4 of FIG. 1.

FIG. 5 is a fragmentary view of the left side elastomeric gasket sealing strip shown in FIG. 2, and the closely adjacent structural elements, drawn to an enlarged scale for clarity.

FIG. 6 is a fragmentary view of the right side elastomeric gasket sealing strip shown in FIG. 2, and the closely adjacent structural elements, drawn to an enlarged scale for clarity.

FIG. 7 is an enlarged fragmentary detail in section illustrating a modification of the first form of the invention wherein the panel to be mounted in edge-sealed relationship comprises a storm window rather than a

screen. This view illustrates this fragmentarily by showing in section a fragment of the left side panel frame portion (corresponding to that shown at the left in FIG. 2) and a fragmentary portion of a window pane carried thereby in lieu of the screen shown in FIG. 2. This corresponds to the junction of the corresponding left side panel frame edge of the window screen panel of FIG. 2 with the left side edge of the window screen itself.

Referring to FIGS. 1-6 for exemplary purposes, one exemplary embodiment of the invention takes a typical exemplary form wherein it comprises the framework means, generally indicated at 11, and which is adapted to be fastened to the window frame or window casing means (or portions) of a window aperture in a wall.

In the specific exemplary form illustrated in FIGS. 1-6, said wall is indicated generally at 12 and terminates in said window frame or window casing portions or means, indicated generally at 13, which surrounds and effectively defines said window aperture, which is generally designated by the reference numeral 14.

In the specific exemplary form of the invention illustrated in FIGS. 1-6, said framework means 11 includes two horizontally spaced, substantially parallel, similar side framework portions, indicated generally at 15, and also includes two vertically spaced, substantially horizontally directed, substantially parallel end framework portions, indicated at 16 in the case of the top end framework portion and at 16' in the case of the bottom framework portion.

Said top and bottom end framework portions 16 and 16' are adapted to be rigidly connected across said side framework portions 15 at the top and bottom ends thereof to define said complete framework means 11 in a substantially rectangular, rigid configuration when fastened with respect to the window frame or window casing portion or means 13. The nature of this fastening will be described more specifically hereinafter.

Each of the two side framework portions 15, and the top and bottom end framework portions 16 and 16' comprise a longitudinal member of substantially L-shaped cross-sectional configuration including two perpendicularly related wing portions joined together and defining an interconnecting vertex portion, with said wing portions being further provided with angularly disposed inwardly directed supporting wall portions or means extending angularly between said wing portions of said longitudinal member on the inner side of said vertex portion joining said two wing portions together and lying in symmetrical angular relationship relative thereto.

The reference numeral 15 designates the longitudinal member of each of the side framework portions comprising same, while the reference numeral 17 designates each of the two perpendicularly related wing portions thereof joined together so as to define the above mentioned interconnecting vertex portion, which is designated by the reference numeral 18.

The above mentioned angularly disposed supporting wall portions or means extending between the wing portions 17 are designated by the reference numeral 19. It should be clearly noted that the opposed angularly disposed inwardly directed supporting wall portions or means 19 of each of the side framework portions 15 defines vertically along the length thereof a longitudinal slot means 20 which comprises a portion of retention means, indicated generally at 21, which will be described in greater detail hereinafter. This is true of each of two longitudinal members comprising the side framework portions 15.

Each of the top and bottom framework portions 16 and 16' comprises corresponding longitudinal members similar to those illustrated at 15 in the case of the side framework portions and described in some detail hereinbefore. Also, each of the top and bottom end longi-

5 tudinal members of L-shaped cross-section 16 and 16', includes two perpendicularly related wing portions defining an interconnecting vertex portion and provided with angularly inwardly disposed supporting wall portions or means and defining a slot means therebetween of a retention means generally similar to the corresponding structures of the side framework portions 15, designated by the reference numerals 17 through 21 and described in some detail hereinbefore.

10 In the case of the top or upper end framework portion 16 (best shown in FIG. 3), said two perpendicularly related wing portions are designated by the reference numeral 22, the interconnecting vertex portion is designated by the reference numeral 23, and the opposed inwardly angularly disposed supporting wall portion or means are designated by the reference numeral 24, while the slot means defined therebetween is designated by the reference numeral 25 and comprises a part of the retention means, generally designated by the reference numeral 26.

15 The lower framework portion 16' (best shown in FIG. 4) includes identical elements to those just described in connection with the upper or top framework portion 16 (best shown in FIG. 3)—identical elements being indicated by identical reference numerals, primed, however. Therefore, further detailed description of said elements of the lower or bottom end framework portion 16' are 20 redundant and unnecessary.

25 The inner angularly disposed supporting wall portions 19 of the side framework portions 15, the corresponding inner angularly disposed supporting wall portions 24 of the top framework portion 16, and the corresponding inner angularly disposed supporting wall portions 24' of the bottom or lower framework portion 16' are provided with compressible, elastomeric sealing gasket strip means indicated by the reference numeral 27 in the case of the side framework portions 15, 28 in the case of the top framework portion 16, and 28' in the case of the bottom or lower framework portion 16'.

30 Said elastomeric sealing gasket strip means may comprise four individual lengths suitable for engagement with the corresponding supporting wall portions or means or may comprise one continuous length extending completely around the inside angularly disposed surface of said supporting wall means of all four of the assembled framework portions 15, 16, 15, and 16' whereby to provide one continuous angularly disposed resilient sealing surface for sealing engagement with corresponding angularly shaped and positioned edge portions of a window screen panel frame, generally designated by the reference numeral 29, and surrounding the complete window screen panel generally designated by the reference numeral 31.

35 Said corresponding angularly positioned edge portions of the window screen panel frame 29 include rear angular abutment surfaces, indicated by the reference numeral 32, and which are adapted to be firmly forced into sealing engagement with said elastomeric sealing gasket strip means indicated at 27, 28, and 28' whenever the window screen panel frame 29 is firmly fastened in locked relationship relative to the framework means 11 and said gasket strip means, such as by the controllably engageable fastening screw means 33 carried by the side edge portions 29 of the window screen panel 31 and also the bottom thumb-operable threaded fastener 33' carried by the bottom window screen panel frame edge 29.

40 In the case of the two side portion fastening screws 33, it should be noted that they extend through the corresponding window screen panel frame side edge portions 29 into threaded engagement with the rear wing portion 17 of the corresponding side framework portion 15 whereby to be firmly, but controllably removably, fastened relative to said side framework portions 15 with the rear abutment surfaces 32 firmly engaging the sealing gasket strip means 27 in sealing relationship therewith.

45 Incidentally, it should be noted that said side frame-

work portions 15 are themselves fastened to the corresponding side window frame portions 13 by suitable threaded fastener means 34 which extend through the side-positioned wing portions 17 of each of the side framework portions 15 directly into threaded engagement with said side window frame or casing portions or means 13. This is clearly shown in FIGS. 2, 5, and 6, and provides a quickly and easily mounting but relatively rigid and strong structural arrangement.

Incidentally, it should be noted that the top and bottom framework portions 16 and 16' are similarly fastened by corresponding fastening screws 35 and 35' to the top window frame portion 13 (best shown in FIG. 3) and to the downwardly angularly inclined window sill portion 36 of the bottom part of the window frame means or portion 13 (as is best shown in FIG. 4).

Also, it should be noted that the top edge portion of the window screen panel frame 29 is removably mounted by engaging apertures 37 over supporting pins 38 which are threadedly fastened at their rear ends, as indicated at 39, to the corresponding rear wing portion 22 of the top framework portion 15, while the bottom edge portion of the window screen panel frame 29 is controllably removably fastened by the lower digitally operable thumbscrew 33' which extends rearwardly through an aperture 30 in said bottom edge portion of the window screen panel frame 29 for threaded engagement with the rear-positioned wing portion 22' of the lower or bottom framework portion 16'.

The above described arrangement provides both a quick and easy means for mounting the entire framework means 11 with respect to the window frame or window casing means or portion 13 and also provides a quick and easy means for sealingly mounting the window screen panel 31 with respect to said framework means 11 and the sealing gasket strip comprising the portions 27, 28, and 28'.

It should be noted that because of the downward inclination of the upper surface of the window sill 36 positioned at the bottom of the window aperture 14, the lower wing portion 22' of the lower framework portion 16' is provided with downwardly directed positioning means comprising the two feet 38 which extend downwardly different distances so as to support the lower framework portion 16' in a proper orientation with one of the wing portions 22' vertical and other of the wing portions 22' horizontal despite the fact that the upper surface of the window sill 36 is inclined downwardly so as to be angularly deflected below a horizontal plane.

It should be noted that while various retention means may be provided for mounting the elastomeric sealing gasket strip means 27, 28, and 28' with respect to the corresponding framework portions, the specific exemplary form illustrated in the figures provides a highly advantageous arrangement since it makes it possible to quickly and easily mount the gasket strip with respect to the framework portions by merely mechanically and elastically deflectably forcing them into retained relationship. Therefore, each of the retention means, 21 in the case of the two side framework portions 15, 26 in the case of the top framework portion 16, and 26' in the case of the bottom framework portion 16', is of identical construction and each comprises first and second elements carried respectively by the rear surface of the sealing gasket strip means and the correspondingly positioned part of the supporting wall portions positioned immediately therebehind.

In the form illustrated with respect to the side framework portions 15, the first element of the retention means 21, mentioned above, comprises an elastomeric, effectively headed projection 39 while the second element comprises the previously mentioned slot means 20. The elastomeric effectively headed projection 39 (which extends along the length of the gasket sealing strip 27) is adapted to be forced through the slot 20 so that the head

39 will then positively retain the sealing strip 27 against the supporting walls 19. The same is true with respect to the headed projection 41 of the sealing gasket 28 of the top retention means 26 which is adapted to be similarly forced through the slot 25 for positive retention purposes. This is clearly shown in FIG. 3.

The above is also true of the elastomeric headed projection 41' carried by the bottom sealing gasket strip 28', which is adapted to be forced through the slot 25' for positive retention purposes similar to those described in detail.

Each of the framework portions is preferably made of extruded metal which can be cut to the required lengths for any particular window aperture. The end cuts of said framework portions can be made at 45 degrees so that they will join together in abutment at the angular 45 degree junction lines clearly designated by the reference numeral 42 in FIG. 1. Said framework portions will be held in said relationship by reason of their being fastened by the threaded fasteners 34, 35, and 35' to the surrounding window frame or window casing portions 13.

Said extruded framework portions are preferably made of a non-corrodible metal, such as aluminum or the like, although not specifically so limited.

The window screen panel frame 29 may be made of similar material or may be made of wood if desired.

The fastening means may be modified substantially within the scope of the invention.

FIG. 7 merely illustrates a slight modification of the invention wherein the panel does not comprise a window screen, as is designated by the reference numeral 31 in FIGS. 1-6, but wherein said panel takes the form of a storm window designated by the reference numeral 31A in this view. All other structural elements are identical to those illustrated in the first form of the invention shown in FIGS. 1-6 and described in detail hereinbefore. Therefore, corresponding parts, in this fragmentary view, are indicated by similar reference numerals, followed by the letter "A," however.

It should be understood that the figures and the specific description thereof set forth in this application are for the purpose of illustrating the present invention and are not to be construed as limiting the present invention to the precise and detailed specific structure shown in the figures and specifically described hereinbefore. Rather, the real invention is intended to include substantially equivalent constructions embodying the basic teachings and inventive concept of the present invention.

I claim:

1. Edge-sealing means for controllably disengageably sealing the edge of a panel to an effective frame means surrounding an aperture in a wall, comprising: framework means provided with fastening means for fastening said framework means to an effective frame means in a wall surrounding and defining an aperture therein, said framework means including two horizontally spaced, substantially vertically directed, substantially parallel, similar side framework portions, and also including two vertically spaced, substantially horizontally directed, substantially parallel, end framework portions adapted to be connected across said side framework portions at the top and bottom ends thereof to define said framework means in a substantially rectangular, rigid configuration, as seen in front elevation, of a size and shape corresponding to and adapted to engage said frame means in said wall surrounding said aperture defined therein, each of said framework portions comprising a longitudinal member of substantially L-shaped cross-sectional configuration including two perpendicularly related planar thin-sheet wing portions joined together and defining an interconnecting vertex portion, each of said wing portions being provided with coplanar thin-sheet angularly disposed and spaced portions of supporting wall means extending angularly inwardly between said wing portions of said member and lying on the inner side of said vertex por-

tion between said two wing portions whereby to lie in symmetrical angular relationship with respect thereto, said angularly disposed supporting wall means being provided with longitudinal compressible sealing gasket strip means coextensive with and lying along the complete length and width of an outer surface of said supporting wall means for forcible sealing engagement with the complete surface areas of correspondingly angularly shaped and positioned edge portions of a panel adapted to be fastened across said aperture in said wall for effectively closing same, said supporting wall means and said sealing gasket strip means being effectively provided with controllably engageable retention means along the lengths thereof for controllably engaging and retaining said sealing gasket strip means against said complete length and width of said outer surface of said supporting wall means in said position for sealing engagement with said correspondingly angularly shaped and positioned edge portions of said panel, said retention means comprising first and second elements carried, respectively, by a rear surface of said sealing gasket strip means and by a correspondingly positioned part of said supporting wall means contiguous with said first element carried by the rear surface of said sealing gasket strip means, said first element of said retention means comprising an elastomeric effectively headed longitudinal projection carried along the length of the rear surface of said sealing gasket strip means, and said second element of said retention means comprising corresponding receiving slot means carried along the length of each of said supporting wall means and defined between said coplanar thin-sheet angularly disposed and spaced portions of said supporting wall means along the length thereof, said first and second elements being resiliently engaged by forcible and temporary deformation of said elastomeric effectively headed projection during insertion thereof through said slot means into a fully retained relationship with respect to said coplanar thin-sheet angularly disposed and spaced portions of said supporting wall means on each side of said receiving slot means.

2. Edge-sealing means as defined in claim 1 including a panel of substantially rectangular configuration similar in size and shape to, but slightly smaller than, said framework means and being provided with abutment edge portions angularly shaped and positioned in correspondence with the angularly shaped and positioned sealing gasket strip means carried by the supporting wall means, said panel being removably receivable within said framework means with said angularly shaped and positioned edge portions in sealing abutting engagement with the correspondingly angularly shaped and positioned sealing gasket strip means.

3. Edge-sealing means as defined in claim 1 including a panel of substantially rectangular configuration similar in size and shape to, but slightly smaller than, said frame-

work means and being provided with abutment edge portions angularly shaped and positioned in correspondence with the angularly shaped and positioned sealing gasket strip means carried by the supporting wall means, said panel being removably receivable within said framework means with said angularly shaped and positioned edge portions in sealing abutting engagement with the correspondingly angularly shaped and positioned sealing gasket strip means, said panel being provided with fastening means for fastening same firmly with respect to said framework means with said angularly shaped and positioned edge portions of said panel in abutting sealing engagement with the correspondingly angularly shaped and positioned sealing gasket strip means.

4. Edge-sealing means as defined in claim 1 including a panel of substantially rectangular configuration similar in size and shape to, but slightly smaller than, said framework means and being provided with abutment edge portions angularly shaped and positioned in correspondence with the angularly shaped and positioned sealing gasket strip means carried by the supporting wall means, said panel being removably receivable within said framework means with said angularly shaped and positioned edge portions in sealing abutting engagement with the correspondingly angularly shaped and positioned sealing gasket strip means, said edge portions of said panel being provided with controllably engageable fastening screw means for fastening same firmly with respect to said framework means with said angularly shaped and positioned edge portions of said panel in abutting sealing engagement with the correspondingly angularly shaped and positioned sealing gasket strip means.

5. Edge-sealing means as defined in claim 1 wherein said end framework portion positioned at the bottom of said framework means is provided with adapter means along the bottom thereof for engagement with a correspondingly shaped lower sill portion of said frame means in said wall surrounding and defining said aperture therein.
